UNITED STATES PATENT OFFICE.

WILLIAM C. BAXTER, OF ROCHESTER, NEW YORK, ASSIGNOR TO EDWARD M. TRIMBLE, OF ROCHESTER, NEW YORK.

FOLDING CRIB.

Application filed October 28, 1924. Serial No. 746,438.

The present invention relates to folding cribs and more particularly to the type in which two side walls are connected by foldable end walls to permit the side walls to be moved toward and from each other. An object of this invention is to improve the manner of folding the end walls so that a stronger hinging connection is provided which insures the folding or unfolding of the end walls without any distortion of the crib. Another object of the invention is to provide a novel hinging means which may also be utilized for locking the end walls in unfolded condition.

To these and other ends, the invention consists of certain parts and combinations of parts, all of which will be hereinafter described: the novel features being pointed out in the appended claim.

In the drawings:

Fig. 1 is an end view of the crib;

Fig. 2 is a plan view showing the bottom swing to a vertical position;

Fig. 3 is an enlarged fragmentary plan view showing the crib in folded condition;

Fig. 4 is an enlarged fragmentary section of one end of the crib;

Fig. 5 is a section on the line 5—5, Fig. 3; and

Fig. 6 is a section on the line 6—6, Fig. 4.

Referring more particularly to the embodiment of the invention herein illustrated, 1 and 2 indicate the two side walls which are connected together by folding end walls.

These end walls, in this instance, each embody a section 3 rigid with and at right angles to the side wall 1 and a section 4 hinged at 5 to the section 3 to swing inwardly.

A novel hinging connection is employed between the section 4 and the side wall 2. This hinging means, in this instance, embodies a vertical bar 6 which through hinges is mounted to turn on a strip 8 fastened to the inner face of the side frame 2, each hinge having leaves 7^a at right angles to each other fastened to the two faces of the strip 8 at right angles to each other and a sleeve 7^b of such hinge connecting said leaves and lying in a plane beyond the outer face of the strip 8. Projecting from the upper and lower ends of the rod 6 are two arms. These arms have portions 9 which when the end

sections 4 are unfolded lie substantially parallel with and on a plane beyond the outer face of said end sections. From the portion 9 a portion 10 extends inwardly in the central opening of the end section, the latter being, in this instance, in the form of a rectangular frame. From the portion 10 a portion 11 extends parallel with the end piece and from this portion 11 a portion 12 is deflected slightly and is pivoted on a pintle 13 rigidly secured to a laterally turned portion 14 on an attaching plate 15, the attaching plate being secured by screws 16 to the outer face of the frame. The portion 11 of the upper arm of the hinging means operates in a horizontal plane slightly below the horizontal plane of the under surface of the upper bar of the end frame 4, while the portion 11 of the lower bar operates in a horizontal plane slightly above the horizontal plane of the upper surface of the lower member of the end frame and projecting from the adjacent surface of said upper and lower pieces of the end frame are rounded projections 17 which as a portion 11 of the hinging means moves inwardly engages with and then moves behind so that the end frame is locked in its normal or unfolded condition. Owing to the fact the two swinging arms are connected by a vertically arranged rod, said arms move together in parallel relation and it is impossible for the crib frame as a whole to become canted or distorted during the folding or unfolding of the crib. Furthermore, as the swinging arms are pivoted to plates fastened by screws to the end frame of the crib, it is possible to attach the ends of the swinging arms after the crib has been substantially completed and in this way insure that the pivotal points are properly positioned on the end frames.

The mattress 18, in this instance, lies upon a mattress supporting frame 19 which in a lower position as illustrated in Fig. 1 rests upon lugs 20 in the side wall 2 and upon plates 21 secured in the corners between the end section 3 and the side walls 1, these plates 21 being formed of sheet metal and providing wide open bearings which permit the swinging of the mattress supporting frame 19 to an upright position as illustrated in Fig. 2. Lips 22 on the plates prevent the sliding of the frame off the plates in the

swinging of the mattress supporting frame from an upright to a lowered position or vice versa.

From the foregoing it will be seen that there has been provided a crib in which the end pieces or frames are hinged in a novel manner. The hinging means are in the form of two arms on an upright portion forming substantially a U-shaped member. These arms connect the top and bottom rails of the side frames by attaching plates which permit the proper positioning of the pivots of the arms. As the arms swing together through the rod connection, a distortion of the crib on the folding or unfolding of the crib is prevented. The arms engage with projections on the top and bottom rails of an end frame to lock the end frame in unfolded condition.

What I claim as my invention and desire to secure by Letters Patent is:

A crib embodying two side walls, a rectangular end frame pivotally connected to one of the side walls having upper and lower rails, a U-shaped member pivotally connected to the other side wall and having its two arms pivotally connected to the rectangular end frame, one arm having a portion operating in a plane slightly below the under surface of the upper rail of the end frame and the other arm having a portion operating in a plane slightly above the upper surface of the lower rail of the end frame, and projections on the opposed faces of the upper and lower rails of the end frame for co-operating with said arms to lock the crib in an unfolded condition.

WILLIAM C. BAXTER.
